UNITED STATES PATENT OFFICE.

OLIVER P. PHILLIPS, OF AMO, INDIANA

INCUBATOR.

No. 874,860.

Specification of Letters Patent.

Patented Dec. 24, 1907.

Application filed October 24, 1906. Serial No. 340,372.

To all whom it may concern:

Be it known that I, OLIVER P. PHILLIPS, a citizen of the United States, residing at Amo, in the county of Hendricks and State of Indiana, have invented new and useful Improvements in Incubators, of which the following is a specification.

This invention relates to incubators of the type embodying a thermostat for automatically governing the temperature within the incubating chamber, being especially directed to an alarm connected with and controlled by the thermostatic mechanism.

The invention has for its objects to provide a comparatively simple, inexpensive device of this character wherein the temperature of the incubator will be properly governed and one wherein an alarm will be sounded for notifying the attendant in the event of the chamber becoming insufficiently or over heated.

With these and other objects in view, the invention comprises the novel features of construction and combination of parts more fully hereinafter described.

In the accompanying drawings: Figure 1 is a vertical sectional view taken centrally and longitudinally through an incubator equipped with an alarm mechanism embodying the invention. Fig. 2 is a detail perspective view on an enlarged scale of a portion of the thermostatic mechanism which controls the alarm.

Referring to the drawings, 1 designates an incubator provided with supporting legs 2 and having an internal incubating chamber 3 adapted for communication through the medium of an inlet pipe 4 with a tubular heating drum 5, beneath which there is arranged a lamp 6, sustained on a suitable supporting bracket 7 and having its chimney 8 extended upward into the drum over the upper open end of which latter there is disposed a movable cut-off plate or damper 9 suspended from the forward end of a regulating lever 10, fulcrumed, as at 11, to swing in a vertical plane and having on its rear end a counterbalancing weight 12.

The foregoing parts, except as hereinafter explained, may all be of the usual or any appropriate construction and material and are adapted in practice to perform their ordinary functions.

Fixed on the top of the incubator casing 1

is a bearing member 13 preferably formed from a sheet metal blank stamped and bent into shape to provide horizontal perforated attaching ears 14, for the reception of fastening members to secure the bearing in place, and vertically-uprising bearing portions 15, while fixed on the lever 10 is a contact plate 16, arranged between the bearing portions 15 and having up-turned longitudinal flanges 17 perforated for the reception of the pintle 11, which in turn is terminally engaged with the bearing portions 15, there being fixed on the plate 16 an outwardly projecting contact arm 18, extended from the plate at right angles to the lever 10.

Sustained in the chamber 3 by means of a bearing yoke 19 carried by hangers 20, is a thermostat 21, the rod 22 of which projects upward through alining openings formed in the top of the casing 1 and bearing plate 13, and is attached at its upper end to contact plate 16 at a point in advance of the fulcrum 11, it being understood that the thermostat, which is of the usual or any appropriate construction, acts under the influence of the heat within the incubating chamber for moving the forward end of lever 10 upward or downward to carry the cut-off plate 9 toward or from the upper end of drum 5 and control the amount of heat delivered into the chamber 3, while the amount of power to be exerted by the thermostat for moving the lever may be controlled at will through the adjustment of the weight 12 on the lever as usual in devices of this class.

Fixed on the top of the casing 1 at a point in advance of and suitably remote from the bearing 13, is a contact member or plate 23 composed of spring metal and having its outer end bifurcated and bent as shown to provide a pair of reversely extended spring contact portions or fingers 24, 25, between which the arm 18 is, under normal conditions, centrally disposed, there being connected with the member 23, which is pivotally secured to the casing by a screw 25', one of the wires 26 of a normally open electric circuit including a battery 27 and an alarm, preferably in the form of a bell 28, the other wire 29 of the circuit being engaged beneath one of the ears 14 and in metallic connection with the contact plate 16 through one of the ears 15 and the pintle 11.

In practice, when the lamp is lighted the air entering the drum 5 becomes heated as usual and passes through the inlet pipe 4 into the chamber 3 for heating the same, the 5 amount of heated air passing into the chamber being of course determined by the position of the cut-off 9 relative to the upper open end of the drum. In the event of the chamber becoming overheated, the thermo- 10 stat 21 will expand and raise the lever 10, thus carrying the cut-off 9 upward and permitting a considerable percentage of the heated air to escape from the drum until the temperature within the chamber has fallen 15 to the requisite degree, or should the temperature in the chamber fall below the desired degree, the thermostat will contract and operate the lever 10 for moving the cut-off 9 downward toward the end of the drum, thus 20 causing a greater quantity of heated air to pass into the chamber. In the event of an abnormal movement of the lever 10, under the action of the thermostat and due to an extremely high or low temperature within 25 the incubating chamber, the arm 18 will contact with one or the other of the fingers 24, 25, thereby completing the electric circuit through the wires 26, 29 to sound the alarm 28, which may of course be arranged at any 30 desired point remote from the incubator. It is to be noted that the arm 18, which is disposed near the pivot 11, will move with the plate 16 in the arc of a circle for scraping contact with the fingers 24, 25, thus insuring 35 positive action of the parts and further that the contact member 23 may, when circumstances require, be turned on the pivot 25' to a position with the contact fingers wholly out

of the path of the arm 18, thus throwing the alarm mechanism out of action. 40

Having thus described my invention, what I claim is:

1. In a device of the class described, a casing provided with a chamber, means for heating the latter, means including a regulating lever for governing the amount of heat supplied to the chamber, a contact arm connected for movement with the lever and disposed at right angles to the latter, a contact member pivoted on the casing and having a pair 50 of spaced contact portions curved in a plane parallel with the lever and between which said arm is arranged for movement, said contact member being movable to a position out of the path of movement of the arm, a normally open circuit including the contact member and arm, and an alarm contained in said circuit. 55

2. In a device of the class described, the combination of a heated chamber, a thermostat therein having a reciprocating member, a swinging plate actuated by the member, a means carried on the swinging plate for regulating the heat supplied to the chamber, a contact on the swinging plate disposed parallel with the axis on which the latter moves, a stationary contact provided with oppositely curved extremities between which the swinging contact is disposed, and a signal circuit controlled by the contacts. 60 65

In testimony whereof I affix my signature in presence of two witnesses.

OLIVER P. PHILLIPS.
